INTERNAL COMBUSTION ENGINE

Herbert C. Edwards, Detroit, Mich., assignor to
 Packard Motor Car Company, Detroit, Mich., a
 corporation of Michigan

Application April 22, 1931, Serial No. 532,013

7 Claims. (Cl. 123—90)

This invention relates to internal combustion engines and more particularly to push rod mechanism.

In engines having their push rods projecting through the crank case so that a portion thereof is in an exposed relation exteriorly of the crank case, oil works out of the rod sleeves or guides. Such leakage of the oil is objectionable and is especially undesirable when the engine is employed as the power plant for an aeroplane because the oil travels rearwardly and spatters the windshield so that the operator's vision is obscured.

An object of the invention is to provide a novel and improved internal combustion engine on which oil leakage through the push rod guides to the exterior of the engine is eliminated.

Another object of the invention is to provide an internal combustion engine having push rods extending through the crank case in which oil in suspension in the crank case is utilized to lubricate the push rod guide sleeves without leakage to the exterior of the engine.

Still another object of the invention is to provide an internal combustion engine in which the push rod and guide structures therefor are utilized to produce suction which will collect lubricant from the bearing surfaces adjacent the exterior end of the guides and return the collected oil under pressure to the crank case.

These and other objects of the invention will appear from the following description taken in connection with the drawing, which forms a part of this specification, and in which:

Fig. 1 illustrates an elevational view of a fragmentary portion of a radial type of engine having portions broken away and in section to show the interior of the crank case and the valve and push rod construction;

Fig. 2 is a fragmentary sectional view of the valve push rod structure taken on line 2—2 of Fig. 1;

Fig. 3 is a similar view of the pump push rod structure taken on line 3—3 of Fig. 1.

In the drawing, 10 represents a barrel-like crank case from which cylinders, as indicated at 11, extend radially and are secured in position therewith by a pair of compression bands 12 which extend around cylinder shoulders 13 which bear against the crank case. A piston 14 is reciprocated within each cylinder and is connected to a crank shaft (not shown) by means of the connecting rod 15 in the usual manner.

The crank case is provided with a rear cover 16 and is divided into compartments by an in-

terior transversely extending reinforcing wall 17. The compartment 18 houses a pair of cams 19 and 20, which are driven from the crank shaft in a conventional manner, and mechanism which is actuated thereby to operate the valve 21 and the pressure fuel injection device which is indicated generally at 22. The valve 21 is arranged to close the interior end of a passage 23 which extends through the head of the cylinder and through which air is drawn into the cylinder and exhaust is expelled therefrom by the piston.

It will be understood that the engine illustrated is of the four-cycle type, the air charges being drawn into the cylinder on the suction stroke and then compressed on the compression stroke during which time atomized liquid fuel under high pressure is injected into the cylinder by the injection device 22. The fuel mixture, so formed, ignites under compression and produces a working stroke which is followed by an exhaust stroke. The valve is normally closed by a plurality of coil springs 24 and is mechanically opened by the rock lever 25 which is pivoted at 26 to a bracket 27 extending above the cylinder head. An enclosing casing 28 surrounds the valve structure and the valve operating rocker. It will be understood that the rocker is moved to hold the valve open during the exhaust and intake strokes, and that the valve is closed by the springs during the compression and working strokes.

A shaft 29 extends transversely of the compartment 18 and is carried by the walls 16 and 17. A pair of slippers 30 and 31 are mounted at one end upon the shaft 29 and are arranged to be rocked respectively by the cams 19 and 20 in their rotation.

An articulated push rod structure is arranged intermediate the slipper 30 and the rock lever 25. This rod structure includes a sectional guide portion 32 in the form of a two-diameter piston, a rod 33 pivotally engaging the piston and the lever 25 and another rod 34 pivoted between the free end of the slipper and the piston. The crank case is formed with an opening for the reception of a guide member 35, or sleeve, with a two-diameter bore in which the push rod section 32 is housed. Suitable fastening means, in the form of bolts 36, extend through flanges 37 on the sleeve for securing the same to the crank case.

The valve push rod piston is formed with a two-diameter bore or passage into which is telescoped a valve housing 58 and a bearing section 39. The valve housing is formed with a shoul-

der 40 which abuts the shoulder formed by the two diameters of the piston bore, and the bearing section is formed with a shoulder 41 for engaging against the inner end of the piston. The sections of the piston are held in axial relation through their association with the rock lever and the slipper.

A passage extends through the piston or guide section of the valve push rod structure through 10 which lubricant is returned under pressure to the interior of the crank case. The board piston is formed with a radially extending opening 42 and complementary to such opening is a circular groove 43 around the valve member so that communication with the radial opening will be maintained regardless of relative rotation. A passage 15 44 extends through the valve member and communicates with the groove therein, while the end of the valve member engaging the bearing section is slotted at 45 so that the passage 44 is intersected. The bearing member is formed with a longitudinally extending passage 46 there-through which communicates with the space between the valve member and the piston and with 20 the interior of the crank case. Within the passage 44 is a one-way valve in the form of a ball 47 which is normally seated by the spring 48. Flow of lubricant through the passage can therefore be only toward the interior of the crank 25 case.

The crank case contains a body of oil which, during engine operation, works between the guide 30 35 and the piston 32 of the push rod structure and lubricates such bearing surfaces. Reciprocation of the piston will normally work the oil through the guide where it would escape from the end exterior of the crank case, but with the structure herein described such leakage of oil is prevented. As the piston moves inwardly of the guide sleeve, suction which will draw any oil from between the smaller diameter portion of the piston and the sleeve back into the larger bore portion of the sleeve. Upon the outward stroke of the piston, the oil which has been drawn or 40 45 which has moved into the larger diameter bore of the sleeve will be placed under pressure by the larger diameter portion of the piston so that it will be moved through the port 42 into the groove 43 and through the passage 44, slots 45 and the passage 46. Thus the oil is trapped and moved through the guided push rod section back into the crank case during reciprocation of the push rod structure.

Within the fuel injection device is a plunger 49, and between such plunger and the slipper 31 is another articulated push rod structure which is similar to the valve push rod structure. A guide member 50, in the form of a sleeve, extends through an opening in the crank case and is secured to the case by bolts 51. The sleeve has a two-diameter bore in which the two-diameter sectional guided portion 52, or piston portion, of the push rod is arranged to be reciprocated. The piston extends through the sleeve exteriorly of the crank case and an adjustable extension 53 is screwed therein, such extension bearing against and operating the plunger of the injection device. The larger end of the piston is formed with an axial bore 54 terminating in a smaller diameter extension portion 55, and screwed into the bore is a bearing member 56. A rod 61 engages in a socket in the bearing member and bears against the slipper 31.

Passages 57 connect the bore extension 55 with 75 the space between the smaller diameter of the

piston and the larger diameter of the guide sleeve, and the bearing member is formed with an axially extending bore 58 in the enclosed end which terminates in a passage 59 which opens into the interior of the crank case. A connection thus extends through the sectional piston to drain oil, which would normally escape to the exterior, back into the crank case from the guide. In the bore 54 is a one-way ball valve 59 held in seated position by the coil spring 60 which is carried in the bore in the bearing member. A lock washer 62 is arranged intermediate the piston and the bearing member to prevent relative rotation thereof.

Oil from the crank case works outwardly between the guide sleeve and the piston 52, and any oil working between the smaller diameters thereof will be drawn back by suction into the larger diameter bore of the sleeve when the piston of the push rod structure moves toward the interior of the crank case. Upon the outward movement of the piston, any oil working or drawn into the space between the larger diameter piston section and the smaller diameter of the sleeve bore will be placed under pressure and forced through the 100 passages 57, the bores 55, 54 and 58, and through the passage 59 into the interior of the crank case.

In both forms of push rod structures, the guided section automatically collects oil by suction and returns the same under pressure back into the crank case through a passageway extending through the piston. As such passageways have a one-way valve associated therein, they are closed during the inward movement of the push rod structures but can be forced open during 110 the outward movement of the rod structures. Through means of such oil control, there will be no leakage through the end of the guides projecting beyond the crank case, although the bearing surfaces of the guides and guided rod sections 115 will be adequately lubricated.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

What I claim is:

1. In an internal combustion engine, a crank case having an opening through its wall, a guide sleeve extending through the opening in the crank case, a push rod structure extending through the crank case wall and including a section mounted to reciprocate in the guide sleeve, and one-way duct means leading from the interior of the sleeve through said push rod section to the interior of the crank case for by-passing lubricant, said push rod structure and said sleeve cooperating to create suction in the duct means in one direction of the push rod structure movement and to create pressure in the duct means in the other direction of the push rod structure movement.

2. In an internal combustion engine, a crank case having an opening through its wall, a guide sleeve extending through the opening in the crank case, a push rod structure extending through the crank case wall and including a piston slidably mounted in the sleeve, said piston having a by-pass extending therethrough for connecting the interior of the sleeve with the interior of the crank case, and a one-way valve in said by-pass.

3. In an internal combustion engine, a crank case having a guide extending through its wall, a push rod structure extending through the crank case wall and including a piston slidably mounted in the guide, and one-way duct means extending through a side of said piston and communicating with the interior of the crank case. 80
4. In an internal combustion engine, a crank case having a guide sleeve extending through its wall, a push rod structure extending through the crank case wall and including a piston portion slidably mounted in the sleeve, said sleeve having a relief intermediate its ends in which oil is collected, and a valved by-pass means through the piston for returning the collected oil to the interior of the crank case, said piston drawing oil into the relief in one direction of its movement and forcing oil through the by-pass in its other direction of movement. 90
5. In an internal combustion engine, a crank case having a guide sleeve extending through its wall, said guide sleeve having a two-diameter bore therethrough, a push rod structure extending through the guide, said structure including a two-diameter piston arranged complementary with the two-diameter bore of the guide sleeve, and one-way duct means through the piston for establishing communication between the larger diameter of the sleeve bore and the interior of the crank case, lubricant being drawn into the larger diameter of the sleeve bore from the smaller diameter thereof by suction when the piston moves inwardly of the crank case and such collected oil being forced into the crank case through the by-pass when the piston moves outwardly in the sleeve. 95
6. In an internal combustion engine, a crank case having a guide sleeve extending through its wall, a push rod structure including a piston slidably mounted in the guide sleeve and a bearing member telescoping into the inner end of said piston, said piston and bearing member having a one-way by-pass extending therethrough for returning oil from the interior of the guide sleeve to the interior of the crank case. 100
7. In an internal combustion engine, a crank case having a guide sleeve extending through its wall, and a push rod structure including a piston slidably mounted in the guide sleeve, a bearing member associated with the inner end of the piston, said piston and bearing member having a passage extending therethrough establishing communication between the interior of the guide sleeve and the interior of the crank case, and a one-way valve in said passageway arranged intermediate the piston and the bearing member. 105
